UNITED STATES PATENT OFFICE.

FOSTER J. HEACOCK, OF CLEARVILLE, PENNSYLVANIA.

CONTAINER.

Application filed August 20, 1927. Serial No. 214,308.

The present invention is concerned with the provision of a container which may have a wide range of utility, but which is peculiarly adapted as a shipping container for 5 fruits and vegetables, particularly apples.

An object of the invention is to provide a container which combines the advantages of both a basket and barrel type container, and yet which eliminates certain disadvantages 10 present in the use of either a barrel or basket.

In connection with the ordinary barrel now commonly employed for shipping apples, a number of disadvantages are found which may be briefly enumerated as follows. 15 An empty barrel is costly to store and ship. The common practice is ring-facing one or two layers of fruit in the bottom of a barrel is both tedious and tiresome inasmuch as the packer must reach down into the full depth 20 of the barrel. Ringtailing, by packing a layer on top of the loose fruit is likewise a tedious process requiring the services of an expert. The empty barrel when received by the packer must be recovered by tightening and 25 nailing the hoops and removing one head and nailing the other in place. The operation of applying a head to a full barrel of apples frequently results in an excessive bruising pressure on the fruit and consequent serious 30 loss from decay. The decayed apples at the top of the barrels present a very poor appearance when the barrel is opened for inspection or sale.

The ordinary bushel basket is quite convenient for storage and shipping purposes when 35 empty due to the fact that a number of baskets may be nested, but it is a poor container for shipment when filled due to the fact that it lacks sturdiness and is not well suited to 40 stacking.

In accordance with the present invention I have overcome all of the above noted difficulties by the provision of a container which includes a pair of tub-shaped sections roughly 45 equivalent to baskets which may be filled and then secured together, end to end, to form a barrel.

By virtue of this construction the container may be shipped as a barrel when full, and 50 shipped as nested baskets when empty. The sections may be readily individually packed without the back-breaking stooping required in packing a barrel. Ringtailing is eliminated. No cooperage by the packer is necessary, since the package is completed at the 55 factory. Any pressure incidental to press-

ing the two sections together is widely and evenly distributed over practically all of the fruit, with a consequent reduction in the number of fruit which are bruised or disfigured. Either end of the barrel may be opened 60 for purpose of inspection or vending, or the barrel may be split in half and opened as two baskets would be opened. Where purchasers desire a half barrel only of apples, 65 one of the containers may be readily split by simply disconnecting the baskets or tubs.

By capping or heading the two basket tops and then placing these heads together at the center of the barrel, an extremely rigid and 70 rugged construction is provided. The container is both simple and practical in construction, well suited to the requirements of economical manufacture, capable of convenient assembly or disassembly, and ready handling, shipping and storing when either full 75 or empty.

With the above noted and other objects in view, the invention consists in certain novel features of construction and combinations 80 and arrangements of parts, as will be more fully hereinafter set forth and pointed out in the claims. The invention may be more fully understood from the following description 85 in connection with the accompanying drawings, wherein—

Fig. 1 is a sectional view through one of the tub-shaped sections of the container showing the latter packed and headed, this view being taken approximately on the line 1—1 90 of Fig. 7.

Fig. 2 is a view partly in side elevation and partly in section showing the two tub shaped sections placed one upon the other, ready to be pressed together, and the retaining straps 95 inserted under the hoops 15, but not yet inserted under the hoops 16 as in their final position.

Fig. 3 is a sectional detail showing the manner of securing the basket lids in place. 100

Fig. 4 is a similar view showing the lids secured and the baskets superimposed.

Fig. 5 is a view similar to Fig. 2, but showing the two sections of the package pressed together with the retaining slats in their final 105 position.

Fig. 6 is a detailed outside elevation of a modification showing the manner of anchoring the ends of the metal securing strips.

Fig. 7 is a sectional plan view through the 110 middle of the barrel.

Fig. 8 is a sectional detail showing the man-

ner of securing the package heads in place when the empty packages are shipped.

Fig. 9 is a fragmentary sectional view on the line 9—9 of Fig. 6.

- 5 In the drawings I have used the reference numerals 10, 10 to designate a pair of approximately tub-shaped sections adapted to be filled with apples or other merchandise to be shipped, then headed with covers 10^a superimposed one upon the other with the covers in engagement pressed together into barrel formation as shown in Fig. 5 and retained in any suitable manner against relative movement.
- 15 Each of the tub-shaped members or baskets 10 are provided with walls consisting of staves held in position at the bottom between inner and outer hoops 12, 13, and at the top between inner and outer hoops 14, 15. Central hoops 16 also encircle the tub-shaped baskets 10. While the walls might consist of a single layer of staves, I preferably form them of a double layer of thin staves, such as staves of veneer. The staves of each layer 25 are slightly spaced apart and overlapped by the staves of the other layer for a purpose which will be more fully hereinafter described.

One of the units 10 is filled and preferably 30 provided with a cap, head, or lid such as 10^a. This lid as best seen in Fig. 7 may consist simply of a circular member formed of crossed slats. Preferably the lid is not placed directly on the fruit in the basket, but lies 35 against a layer of packing and cushioning material such as the disc 17 of corrugated paper or equivalent material.

The bottom 18 of each basket 10 is preferably made of two layers of slats placed crosswise to each other, and properly spaced if desired, to afford ventilation. Various expedients might be resorted to for securing the lids 10^a. I have shown one convenient means of attachment in which metal straps 19 carried 45 by the inner hoops 14 are provided with bendable ends 20 adapted to be bent inwardly over the edges of the lid 10^a.

In many instances it is not essential to use 50 a lid on both baskets, although I have illustrated two lids in the drawings. Obviously, the only place where a lid is essential is on the basket which must be inverted and emplaced on top of a lower one.

With the two baskets superimposed as in 55 Fig. 2, they are placed in any suitable press, or any suitable means is utilized for forcing them together until the hoops 14 and 15 of the two baskets abut. Ordinarily the lid 10^a will belly out slightly when first applied, and 60 the pressure necessary for flattening them when the baskets are assembled to form a barrel is just sufficient to insure tight and proper packing of the fruit.

Numerous means might be utilized for retaining the two baskets together so that they

may be shipped as a barrel unit. Preferably, wooden staves, strips or slats such as 21 are inserted under the encircling hoops 15, 16 of the baskets and nailed in place. In an alternate embodiment of the invention however, 70 the securing strip-like members 21' are of metal. They lie in the space between the outer staves of the baskets under the hoops 15 and 16 and their bendable ends 22 are turned back around the hoops 16 as shown in Figs. 6 and 75 9, whereby the two baskets are securely retained against relative separation. The turned back ends 22 may be nailed or otherwise secured at 23 to the hoops 16 if desired. The use of the securing strips, slats or staves 80 in the spaces between the outer basket staves also serves to lock the two baskets against relative sliding or relative rotary movement.

From the foregoing description it will be seen that the two baskets may be packed with 85 the facility of ordinary bushel baskets; that, when shipped together they retain all of the advantages of a barrel as a shipping container, and that when they are received by the consignee they may be readily separated 90 and sold as basket units if desired, or either head of the barrel may be opened.

When the container is filled the heads 18 of the baskets will be retained in place by the weight of the fruit. When the baskets are 95 shipped empty however, some supplemental means must be provided for holding the heads. Such means has been illustrated in Fig. 8, wherein it will be noted that the heads may either be directly nailed in place or secured by a circular cleat such as 18^a.

Various changes and alterations might be made in the general form and arrangement of the parts described without departing from the invention. Hence I do not wish to limit 105 myself to the details set forth, but shall consider myself at liberty to make such changes and alterations as fairly fall within the spirit and scope of the appended claims.

I claim:

1. As a new article of manufacture, a container for shipping fruit or the like, including a pair of substantially tub-shaped basket-like sections adapted to be filled with fruit and placed mouth to mouth, each basket-like section consisting of staves and inner and outer rings at their ends, means for securing said sections rigidly together against relative movement in any direction whereby a barrel-like container is formed, a lid for one basket section constituting in the assembled sections a central reinforcement for the container, and straps having one end adapted to bend around the inner rings and having their other ends adapted to be bent down on the lid to hold the same in place when the basket-like section is inverted and emplaced on its companion basket-like section.

2. As a new article of manufacture, a container for shipping fruit or the like, includ-

ing a pair of substantially tub-shaped basket-like sections adapted to be filled with fruit and placed mouth to mouth, means for securing said sections rigidly together against relative movement in any direction whereby a barrel-like container is formed, each basket-like section being formed of staves and stave-retaining rings at its ends, and anchoring means comprising staves passed under said

10 rings and anchored to the basket-like sections.

3. A container for shipping fruits and the like, comprising a pair of substantially tub-shaped basket-like sections adapted to be placed mouth to mouth after being filled, 15 each section being formed of two layers of

overlapping slats, the slats of each layer being spaced from one another, inner and outer rings at the ends of the sections and intermediate rings between the ends of the sections, and securing strip-like members passing between the rings at the open ends of the sections and lying in the space between the slats of the sections with their ends lying under the intermediate rings of the said sections.

Signed at Bedford, in the county of Bedford and State of Pennsylvania, this 17th day of August, A. D. One thousand nine hundred and twenty-seven.

FOSTER J. HEACOCK.
